DESCRIPTION

U.S. PATENT DOCUMENTS

2003/0141424 A1 * 7/2003 Thomas B60N 3/103
248/311.2

FIG. 1 is an elevated perspective view of the removable magnetic cup holders for a grill of the claimed design;
FIG. 2 is a front view of the cup holders of FIG. 1;
FIG. 3 is a back view of the cup holders of FIG. 1;
FIG. 4 is a right side view of the cup holders of FIG. 1;
FIG. 5 is a left side view of the cup holders of FIG. 1;
FIG. 6 is a top view of the cup holders of FIG. 1; and,
FIG. 7 is a bottom view of the cup holders of FIG. 1.
